UNITED STATES PATENT OFFICE

CHARLES DOBBIN, OF BROOKLYN, NEW YORK, ASSIGNOR TO UNITED STATES MAIL CHUTE CORPORATION, OF NEW YORK, N. Y., A CORPORATION OF NEW YORK

MAIL CHUTE

Application filed April 24, 1930. Serial No. 446,846.

This invention relates to a mail chute or a conduit made to extend from the upper to the lower floor of a building and by means of which letters, or other matter for the mail, 5 may be placed in the chute on any floor and permitted to drop to a letter box or other receptacle provided for this purpose on the first floor, or basement, or other place in the building. In mail chutes of the type to 10 which my invention relates it has been customary to employ a plurality of channel members which interfit with each other at the ends thereof, and to also employ removable panels which are suitably supported and the parts maintained in their operative positions 15 by a band surrounding the same and locked in place to prevent unauthorized persons from tampering with the chute. The construction of the apparatus to which the invention more particularly relates is also such that upon unlocking the band the panel members may be removed to clear the chute when 20 necessary, or for other purposes.

Now in an apparatus of this kind it has 25 been found that in removing the panel members the interfitting parts of the channel members become disconnected and it is more or less difficult after the chute has been installed to restore these channel members to 30 their proper positions in their necessary relationship to one another. The object of my invention is to overcome this difficulty and to so construct the channel members and connect them to one another in the installation 35 of the apparatus that they cannot become disconnected or deranged when it is necessary to remove the panel members for clearing the chute, or any other purpose. To this end in carrying out the invention the adjacent ends of the channel members are interfitting and one channel member, preferably an upper channel member, is provided with a device for engaging the adjacent portion 40 of a lower channel member in such a manner that they cannot become disassociated from one another, as will be hereinafter more particularly described.

In the drawing Figure 1 is a sectional plan 45 illustrating a mail chute made in accordance with this invention,

Fig. 2 is a sectional elevation on line 2-2, Fig. 1, and

Fig. 3 is a sectional elevation on line 3-3, Fig. 1.

Referring to the drawing it will be seen 55 that in carrying out the invention the mail chute made in accordance therewith is constructed to include a plurality of channel members made of sheet metal, or other similar material, and to be placed so that the 60 lower end of one channel member is within the upper end of the next adjacent lower channel member. In the drawing one channel member is indicated at 10 and another channel member is indicated at 11. Each of these 65 channel members is constructed to include a back 12 and sides 13 and 14.

The mail chute proper is completed by employing a panel with each of the channel members. These panels are preferably made 70 of plate glass fitted with a suitable frame of metal, or other material.

As illustrated the panel associated with the channel 10 comprises a glass plate 15 and a metal frame 16. The panel associated with 75 the channel 11 comprises a glass plate 17 and a metal frame 18.

The interfitting ends of the successive channel members are preferably located at a suitable distance above each floor of a 80 building and between the same and the ceiling. At the juncture point between the channel members the chute includes a band. This band is preferably made of metal and comprises a back member 19, side members 85 20 and 21, a front member 22, which at one end is pivotally connected to the extremity of the side member 20 as indicated at 23, and an arm 24 pivotally connected, as indicated at 25, to the opposite end of the front member 22. The arm 24, when the parts are in 90 their normal positions, is adapted to lie against the outer face of the side member 21 and is provided with a suitable lock 26 by means of which the arm 24 and consequently the front member 22 are secured in 95 place to maintain the parts of the chute in their assembled positions. As illustrated this band may include a cross bar 27 pivotally mounted at one end in the arm 20 and adapt- 100

ed at its opposite end to engage the arm 21 so that when in place it functions to support the panel comprising the plate 15 and the frame 16. This construction is more particularly shown and described in my application Serial No. 368,774, filed June 6th, 1929.

The front member of the band is preferably constructed to include an offset 28 in the upper portion of which there is a letter slot 29 for the admission of letters or other matter for the mail.

Beneath the letter slot there is a pivotally mounted spring actuated flap 30, or other equivalent device, for normally maintaining the slot closed. The lower end of the frame 16 of the panel associated with the channel 10 is preferably provided with an apron 31 depending from the frame sufficiently far to extend below the latter slot 29 in order to prevent letters when inserted through the slot from interfering with letters which may be simultaneously descending through the channel member 10.

The band member may be secured to wall plates 32, or directly to the wall by means of screws 33 or otherwise. The lower end of each channel member is provided with a device for engaging the upper end of the next adjacent channel member. For example, as illustrated the channel member 10 may be fitted with a plate 34 adapted to lie within a recess 35 provided therefor in the back 19 of the band member and the plate 34 provided with an offset or hook portion 36 forming a pocket between the same and the adjacent outer surface of the back of the panel member for the reception of a portion of the upper end of the back member of the channel 11, in order, as will be understood, to permanently fix the channel members to one another at their interengaging ends and thereby prevent either one or both of these channel members from becoming dislodged during the removal of the panels which are associated therewith. Of course, it will be understood that any suitable means equivalent to the plate 34 may be employed for this purpose and that the plate, for example, may be associated with the lower rather than the upper chute member and constructed so as to engage the upper channel member and connect the parts one to the other without departing from the nature and spirit of the invention.

I claim as my invention:

1. In a mail chute, a lower channel member, an upper channel member having its lower end fitting within the upper end 60 of the lower channel member, a lock band surrounding the interengaging ends of the channel members and having a recess in the back member thereof, and a plate having an offset portion for engaging the upper 65 end of the lower channel member to main-

tain the channel members in their operative relationship one to another, the said plate and its offset portion being adapted to lie within the said recess in the back of the said lock band.

2. In a mail chute, a lower channel member, an upper channel member having its lower end fitting within the upper end of the lower channel member, a band associated with said interengaging ends of the channel members, said band comprising a stationary portion having a recess therein, and a pivotable portion having a locking means mounted thereon, a plate having an off-set portion for engaging the upper end of the lower channel member to maintain the channel members in their operative relationship one to another, the said plate being locked within the recess of the stationary portion of the band when the pivotable portion is in its closed position.

Signed by me this 24th day of March, 1930.
CHAS. DOBBIN.
